THERMAL BACK PART CONDITIONER FOR SHOE UPPERS

Addison W. Closson, Jr., Cambridge, Mass., assignor to Beckwith-Ardon Inc., Watertown, Mass., a corporation of New Hampshire

Filed Sept. 11, 1961, Ser. No. 137,393
6 Claims. (Cl. 12—59.7)

This invention comprises new and improved apparatus for conditioning by heat the back or counter part of a shoe upper while on the last so that it may be given the molded contour of the last directly from the last without requiring an intermediate molding operation.

It is, of course, desirable for many reasons to obviate the necessity of employing a stiff premolded counter in the back part of a shoe. Such practice involves the purchase of molded counters from an outside source of supply at considerable expense and with risk of mistakes as to size and shape. Then, the operation of pasting and inserting a molded counter stiffener requires considerable skill and experience, and finally the molded counter, even if properly placed, is likely to prevent the upper from making perfect contact with the last, particularly about the margin of the heel seat.

An object of the present invention is to provide apparatus for softening and rendering adhesive or conditioning on the last an upper that has already been assembled with a ply of thermoplastic sheet material as a part of the counter lining or an interleaved blank.

I have discovered that by proper conditioning of the back part of an upper so prepared the desired molded shape may be achieved by immediately pulling over and lasting the heel seat end of the shoe upon the last. The whole counter portion of the heated upper is thus conformed directly to the surface of the last and stiffens in the molded shape thus acquired without supplementary or intermediate molding operations.

The herein described apparatus includes an underlying steam chamber and an overhead casing presenting forwardly opening hoods, a rearwardly inclined forepart supporting plate and means for supporting the rear end of an upper-carrying last with the entire counter portion of the upper enclosed and subjected to heat from the steam chamber.

Preferably and as herein shown the overhead casing is constructed and arranged to support the assembled upper upon the last in inverted position since the upper is thus most effectively exposed to a rising current of superheated steam or other heating medium.

These and other features of the invention will be best understood and appreciated from the following description of a preferred embodiment thereof selected for purposes of illustration and shown in the accompanying drawings in which:

FIG. 1 is a view of the apparatus in front elevation,
FIG. 2 is a plan view,

FIG. 3 is a sectional view on the line 3—3 of FIG. 1,

FIG. 4 is a view in perspective of a portion of the overhead casing,

FIG. 5 is a sectional view illustrating a modified form of the overhead casing, and

FIG. 6 is a view in perspective of a portion of the modified casing.

The conditioning apparatus herein shown is constructed of sheet metal and comprises walls forming the elongated underlying steam chamber 10 through which passes a perforated steam pipe 11 inclined to an outlet elbow at one end of the chamber. The upper portion of the chamber contains a perforated horizontal partition 12. It may be flat or as herein shown transversely concave so that in general steam passing through it will be directed up-

2

wardly and inwardly toward its longitudinal axis of curvature. The partition is supported at its sides by angle irons secured to the walls of the steam chamber. Above the partition is located an electric heating unit 13 controlled from a switch box secured to the left end of the steam chamber as shown in FIGS. 1 and 2. The heating unit may take the form of a tubular infra-red lamp as described for example in United States Patent 2,970,331 Gaquin.

Above the steam chamber and telescopically fitted into its upper portion is an overlying superstructure 14 forming a long closed chamber supported by inturned flanges resting upon the side edges of the partition 12 as shown in FIG. 3. The front wall of the superstructure carries a rearwardly and downwardly inclined plate 16 for supporting the forepart of an upper-carrying last. The superstructure also includes a series of U-shaped forwardly opening hoods 15 which extend forwardly over about one-half the area of the supporting plate 16 and open freely into the underlying steam chamber. The plate 16 extends continuously and serves the entire row of hoods 15. A transverse rod 17 crosses the open space beneath each hood in position to engage and support the rear end of the last or the upper assembled thereon. The rods 17 are of small diameter and do not interfere with a copious upper flow of superheated steam from the underlying steam chamber.

In FIG. 3 the upper-carrying last is shown as located within a hood 15 in upright position with its forepart resting upon the plate 16 and its entire back part enclosed within the hood 15 and supported by spot contact with the rod 17.

In FIGS. 5 and 6 the superstructure of the apparatus is shown as slightly modified to receive the upper-carrying last in inverted position. This has proved to be particularly effective in conditioning the counter portion of the upper since the sides of the upper diverge upwardly upon the heel portion of the last and so are somewhat more directly exposed to the rising body of superheated steam required for conditioning the upper. In this modification of the apparatus the hoods 15 and rods 17 remain the same but the inclined supporting plate 20 is recessed or notched at 21 to receive the projecting instep portion of the last. The back cone part of the last is thus supported partly by line contact with one of the rods 17 and partly by wedging engagement of its instep portion in a tapering recess 21 of the supporting plate 20.

The process in which the illustrated apparatus is employed may be characterized by the steps of placing a thermoplastic blank in the counter pocket of an upper, assembling the upper on the last, heating the whole counter portion of the upper while upon the last, pulling over the heated upper and thus forming its whole back part to the contour of the last. When this has been done the upper is allowed to cool and stiffen upon the last, although it is desirable to have the heel seat lasting operation immediately follow the pulling over step if possible.

Thermoplastic sheet material suitable for carrying out the above process is commercially available in several forms, for example, that disclosed in United States Patents No. 2,611,726 September 23, 1952 Harrison; No. 2,619,441 November 25, 1952 Levy and No. 2,390,347 December 4, 1945 Beckwith and Swett.

The infra-red energy supplied by the quartz lamp tube 13 has been found particularly effective and desirable for both superheating the rising steam and heating the material of the upper on the last, although the precise form of the heater is of secondary importance.

In some cases it has been found desirable to curtain the opening of the hoods 15 as suggested in FIG. 6 by hanging a strip of textile material 18 over their upper

portions. The upper-carrying lasts may be inserted beneath this strip while the strip acts to hold the rising steam in contact with the upper.

Having thus disclosed my invention and described in detail an illustrative embodiment thereof, I claim as new and desire to secure by Letters Patent:

1. Counter conditioning apparatus for unlasted shoes, comprising an underlying steam chamber having an electric heater extending through its upper portion, and an overhead casing including a series of forwardly-opening U-shaped hoods, a rearwardly and downwardly inclined forepart supporting plate extending continuously and serving all said hoods, and a transverse rod below each hood for supporting by point contact the heel end of a last with the counter portion of an assembled upper thereon in a position above the said electric heater.

2. Counter conditioning apparatus as described in claim 1, further characterized in that the means for supporting the rear end of the upper-carrying last comprises a rod making only line contact with the last and so exposing the entire counter portion of the upper to steam rising from the steam chamber.

3. Counter conditioning apparatus for unlasted shoes, comprising an underlying steam chamber and an overhead casing including forwardly opening hoods in communication with the steam chamber, a back cone-supporting rod for the last above the steam chamber and beneath each hood, and an inclined plate fronting the hoods and recessed to receive the instep portion of the last and hold it in inverted position with an upper assembled thereon.

4. Counter conditioning apparatus for uppers assembled with a thermoplastic component, comprising an underlying steam chamber, means for supporting by point contact an upper-carrying last in inverted position above the

steam chamber, a hood projecting into free space, enclosing the whole rear part of the lasted upper and disposed in free communication with the steam chamber, and a source of infra-red energy located in position both to superheat steam rising from said steam chamber and heat the counter portion of the upper on the last.

5. Counter conditioning apparatus as described in claim 4, further characterized in that the opening of the hood is partially curtained by a textile sheet under which the inverted last may be inserted.

6. Apparatus for heat-conditioning the counter portion of an upper on a last, comprising an elongated underlying steam chamber of sheet metal having an electric heater in its upper portion, and an overhead casing including a series of forwardly-opening U-shaped hoods communicating with said steam chamber, a rod located below each hood for supporting by point contact the rear end of an upper-carrying last in a position freely exposed to steam rising from the underlying steam chamber, and means cooperating with said rod for supporting the forepart of the upper-carrying last in a rearwardly and downwardly sloping position with the counter portion of the upper located above the electric heater.
